UNITED STATES PATENT OFFICE

LLOYD B. WHITTAKER, OF WHITE PLAINS, NEW YORK, ASSIGNOR TO HOLLAND-RANTOS COMPANY, INC., OF NEW YORK, N. Y., A CORPORATION OF NEW YORK

MEDICAL APPLIANCE

Application filed December 10, 1931. Serial No. 580,038.

This invention relates to medical appliances and is adapted more particularly to facilitate the introduction of medicaments and the like in liquid, semi liquid or jelly form into particular passages of the human body.

More specifically, the invention is especially adapted for employment in facilitating the introduction of medicinal jellies into the vaginal canal for direct application to the cervix.

Medicinal jellies which are generally used in this connection are commonly packaged in collapsible tubes, and great difficulty is experienced in applying the jelly from such tubes to the stated parts of the human body. The more common practice is to squeeze a portion of the jelly from the tube on to a suitable applying implement and thereupon attempt to make the application through the employment of such implement. Experience has shown, however, that in a majority of cases where this is attempted, the jelly does not reach the point of desired application, but is removed from the implement before such point is reached. Furthermore, in utilizing the separate and independent implement for the purposes stated, unsanitary conditions are apt to result with consequent infection.

With the foregoing considerations in mind, the object of the present invention is to provide a medical appliance adapted to be associated directly with a collapsible tube by securing the appliance on to the threaded neck of the tube after removal of the conventional cap therefrom.

In its preferred practical form, the invention comprises a cylindrical tube which, in practice, may conveniently be made by wrapping one or more strips of paper about a suitable mandrel and adhesively securing the superimposed plies or laminations to one another to produce a rigid permanent structure. The tubular structure which results

has an inner diameter slightly less than the threaded neck of the collapsible tube with which it is adapted for use. It has a free and unobstructed opening at one end adapted to cooperate with the tube neck 50 while the opposite end is crimped inwardly so as to impart a somewhat rounded configuration to said end of the appliance, whereby it will not scratch or injure the body tissue during passage through the introitus and vaginal canal.

Features of the invention, other than those specified, will be apparent from the hereinafter detailed description and claim, when read in conjunction with the accompanying drawing.

The accompanying drawing illustrates one practical embodiment of the invention, but the construction therein shown is to be understood as illustrative, only, and not as defining the limits of the invention.

Figure 1 is a side elevation of an appliance embodying the present invention showing the same operatively associated with a collapsible tube, one end of which is shown 70 in this figure.

Figure 2 is a view similar to Figure 1, but showing the opposite end portions of the appliance in central section, so that the structure of the device will be apparent.

Referring to the drawing, 1 designates the appliance of this invention. It is in the form of a hollow tubular body of cylindrical configuration and in practice is preferably constructed of relatively soft fibrous material, such, for example, as paper. It can conveniently be made by sparingly wrapping strips of paper over one another to form a laminated tube-like structure of a multiplicity of plies, there being four plies 85 shown in the drawing.

As the plies are wrapped, they are adhesively secured together to form a rigid structure which will retain its shape under ordinary conditions of use and at the same 90

time be not so rigid as to be uncomfortable in particular cases. The interior portion of the tube may to advantage be coated with some moisture repelling substance such, for example, as paraffin wax, so as to present a liquid impervious surface to material passing through the tubular structure. The external surface may be similarly coated although, in practice, I find it convenient to use a glazed paper for the outermost ply and to thereby produce a substantially frictionless surface which will not rub or chafe, but will slide freely over the most delicate tissues. The tube is wrapped in the manner described with a wall of substantially uniform thickness throughout and of substantially uniform diameter. One end of the tube is thereupon flanged or crimped inwardly as indicated at 2, so as to produce a rounded or tapered end which, when brought into contact with the body tissue will not scratch, abrade or harm the same in any way.

The tubular section is made of a diameter slightly smaller than the threaded neck 3 of a collapsible tube 4 with which the device is adapted to be used. These collapsible tubes are of conventional form and the size of the neck is practically standard. As a matter of fact, it is preferable that the interior diameter of the device 1 be substantially equal to the diameter of the neck at the base of the threads.

Inasmuch as the material entering into the tubular structure is of paper which may be generally characterized as relatively yieldable fibrous material, it is apparent that when so shaped and proportioned this device may be screwed upon the neck 3 of a collapsible tube and the act of applying the device as stated to the tube will cause the threaded neck of the tube to cut threads in the inner surface of the device and to thereby provide a threaded connection between the parts which will firmly hold the device in place on the tube. When the parts are assembled as stated, the collapsible tube together with the medical appliance of this invention constitute collectively an instrument for the application of medicated jellies direct to the cervix, it being apparent that the length of the tubular part 1 is such that it may be inserted into the passage to bring the outlet end of the part 1 into substantially juxtaposition with the cervix, whereupon compression of the collapsible tube will cause the jelly to be exuded from the collapsible tube and from thence to pass through the passage of the device 1 to be in turn exuded from the outlet end of said device for application direct to the cervix.

The device of this invention is economical to manufacture and is intended primarily for a single use and to thereupon be dis-

carded or thrown away. The tubes are packed in a way to render them sanitary and to keep them free from impurities so that when removed from the package and applied to the collapsible tube medicated jelly will pass in a thoroughly hygenic condition directly from the tube to the point of application and thereby minimize or entirely eliminate the possibility of infection due to the employment of extraneous and independent implements such as has heretofore been the practice.

In the drawing, I have for the purpose of illustration shown the device on somewhat enlarged scale, but, in practice, the device is relatively small and the passage through the device is less than the diameter of the tube so that there is very little jelly waste even when the device is used for a single application and thereupon discarded.

The device of this invention, being adapted as it is to use with conventional collapsible tubes and forming in effect an adjunct to be used in connection therewith, fulfills a long felt want in the art to which it particularly relates.

The drawing and foregoing detailed description sets forth the invention in its preferred, practical form, but the invention is to be understood as fully commensurate with the appended claim.

I wish to lay particular emphasis upon the fact that the appliance of this invention is unusually economical. It may conveniently be manufactured from paper at a cost which is nominal and distributed to the trade gratuitously with tubes containing the jelly with which it is adapted to be used.

Having thus described the invention, what I claim as new and desire to secure by Letters Patent is:

A medical appliance comprising a hollow paper tubular body, one end of which is crimped inwardly to form a tapered or rounded end which will not scratch or abrade human body tissue and the other end of which tube has a free and unobstructed opening of an internal diameter slightly less than the diameter of the threaded neck of a conventional collapsible tube, whereby the open, unobstructed end of the tubular body may be screwed on to the threaded neck of such collapsible tube to cause the threads of the collapsible tube to form threads in the tubular body to place the surrounding portion of the tubular body under tension for the purpose of firmly and detachably mounting the tubular body on the collapsible tube against inadvertent displacement.

In testimony whereof, I have signed the foregoing specification.

LLOYD B. WHITTAKER.
